UNITED STATES PATENT OFFICE.

JOB GIBBS HANN, OF GRAND RAPIDS, MICHIGAN.

BICYCLE-LOCK.

SPECIFICATION forming part of Letters Patent No. 710,576, dated October 7, 1902.

Application filed October 15, 1901. Serial No. 78,751. (No model.)

To all whom it may concern:

Be it known that I, JOB GIBBS HANN, a citizen of the United States, residing at Grand Rapids, in the county of Kent and State of Michigan, have invented a new and useful 5 Bicycle-Lock, of which the following is a specification.

This invention is an improved construction of lock, the object being to provide an exceedingly cheap and simple lock which can be applied to the front forks of a bicycle for the purpose of locking the front wheel whenever it is desired to prevent the removal of the wheel.

With this object in view the invention consists in the peculiar construction of the various parts and in their novel combination or arrangement, all of which will be fully described hereinafter, and pointed out in the 20 claim.

In the drawings forming part of this specification, Figure 1 is a perspective view illustrating the practical application of my invention. Fig. 2 is a sectional elevation showing 25 the position of the parts when the lock is not in use. Fig. 3 is a similar view showing the position of the parts when the bar is locked. Fig. 4 is a detail perspective view illustrating the locking-bar as arranged when not in 30 use. Fig. 5 is a detail section illustrating the swivel connection with the locking-bar. Fig. 6 is a section on the line 6 6 of Fig. 2. Fig. 7 is a vertical section on the line 7 7 of 35 Fig. 3. Fig. 8 is a view illustrating the tumblers and bolt. Fig. 9 is a view illustrating the spring-actuated slide and casing for the same.

In carrying out my invention I employ a locking-case A, which is provided with suitable ears or cleats A', by means of which it is attached to one of the forks of the machine, the case being arranged upon one of the forks, the locking-bar B being attached to the opposite fork and is adapted to extend across 45 the space between the forks, and therefore occupy a position between the spokes, whereby the rotation of the wheel is prevented. The bar B has a head B', which is connected to the swivel B², carried by the clip B³, the opposite end of the bar being bent, as shown at B⁴, and notched, as at B⁵. A spring-clip B⁶ is also attached to the fork below the clip B³

for the purpose of holding the locking-bar when not in use.

Within the case are arranged the tumblers 55 and locking-bolt, and referring particularly to Fig. 8, C represents one of the tumblers, D the other one, and E the locking-bolt. The tumblers are pivoted upon a post F and are normally projected forwardly by means of 60 the springs C' and D', respectively, which engage notches C² and D², respectively. The bolt has a post or lock E', which is adapted to engage one of the series of notches C³ and D³ of the tumblers, and this bolt also has a 65 locking member E², which is adapted to engage the notched end of the locking-bar B⁵, a spring E³ normally forcing the bolt in a forward direction.

G indicates a casing arranged within the 70 lock-case and communicating with the opening G', through which the end B⁴ of the locking-bar is inserted, and sliding in the casing G is an inverted-U-shaped plate H, a spring I being arranged within the casing and sliding 75 plate for the purpose of normally projecting the said plate upwardly for the purpose of closing the opening G'. The casing G is cut away at one side, so that when the end of the locking-bar is pushed into the case and 80 the sliding plate forced down the locking member E² of the bolt can spring into engagement with the notched end of the locking-bar.

C⁴ and D⁴ indicate the respective portions 85 of the tumblers which are adapted to be engaged by the key for the purpose of throwing the tumblers out of engagement with the locking-bolt, and the key then contacts with the member E⁴ and will serve to move the 90 bolt rearwardly, releasing the locking-bolt, and the spring-actuated sliding plate will immediately project the same out from the case. The locking of the bar is of course accomplished without the aid of the key, as it is 95 only necessary to push the notched end of the bar into the opening G' and the spring-actuated bolts and tumblers will serve to securely lock the bar in its position.

Having thus fully described my invention, 100 what I claim as new, and desire to secure by Letters Patent, is—

The combination with a locking-case, of the tumblers C and D pivoted within the case and

having springs connected thereto, a locking-bolt arranged within the case and having a locking member, a post or lug adapted to engage the tumblers, and a member adapted for engagement with the bit of the key, a casing open at one side, and an inverted-U-shaped plate sliding in the casing, a spring contained within the case and plate, the lock-

ing-case having an opening communicating with the case and a locking-bar having a notched angular end, substantially as and for the purpose described.

JOB GIBBS HANN.
